Patented Dec. 22, 1925.

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

LAST SUPPORT.

Application filed October 6, 1922. Serial No. 592,827.

To all whom it may concern:

Be it known that I, JOSEPH H. POPE, a citizen of the United States, residing at Hamilton, in the county of Essex and State of Massachusetts, have invented certain Improvements in Last Supports, of which the following description, in connection with the accompanying drawings, is a specification, like reference characters on the drawings indicating like parts in the several figures.

The present invention relates to devices for supporting lasted shoes for operations upon them, as the attachment of the heels, and is more particularly concerned with the protection of the lining or other portion of the upper against being caught between the last and its support when the lasted shoe is jacked or is put under pressure during the operation.

Objects of my invention are to provide a simple, inexpensive and efficient protective device which will act substantially simultaneously about the entire support. These objects I attain through the employment of a continuous member surrounding the support and movable toward and from the jacked shoe thereon. Preferably, this member is expansible, being shown as in the form of a helical spring arranged for contact with the interior of the shoe. In the illustrated embodiment of the invention, the member upon which the last is supported includes relatively movable sections, between which the encircling spring is movable outwardly under their influence. This single work-engaging member, wholly without other movable supports than those which it surrounds and free from pivoted connections, gives the desired continuity of action and contact with the lining about the interior of the shoe, thrusting said lining away, uniformly in all directions, from the support when the last is pressed into engagement with it. When the last member of the support is arranged for oscillation to better position the work for the operations upon it, the lining protector is best carried by the member, so that its relation to this element and to the supported work is maintained constant.

One form which my invention may assume appears in the accompanying drawing,

Fig. 1 showing, in side elevation, a last-support or jack, with its lining-protector, 55 as a part of a heeling machine;

Fig. 2, being an end elevation of the jack with portions in section on the line 2—2 of Fig. 1;

Fig. 3, a plan view of the jack-top; and 60

Fig. 4, a vertical section therethrough on the line 4—4 of Fig. 3.

The numeral 10 designates a jack of a heeling machine, as of the Lightning type, with its associated toe-rest 12 and the die-block 14, with which it co-operates. Carried at the top of the jack is a last-slide 16, mounted to move transversely in ways 18 so that the work may be correctly positioned beneath the die-block-openings. In 70 the slide is formed a socket 20 adapted to receive a generally spherical head 22 upon a last-pin 24. Furnishing the upper portion for this socket and being secured in place upon the slide by screws 26 is a plate 28, 75 overhanging the head 22 at an opening registering with the top of the socket. The last-pin 24 is designed to enter the vertical bore *b* in the cone *c* of a last *L*, it giving, by virtue of its oscillation in the socket, a lateral adjustment to permit the work to 80 conform to the pressure applied to it by the operating elements of the machine, as when the heel *H* which is to be attached to the lasted shoe *S* is pressed against the under side of the die-block 14 preparatory to driving the heel-attaching nails. A contact-projection 33, preferably cylindrical in 85 form, depends from the under side of the head 22, and, by its contact with the lower 90 cylindrical portion of the socket, limits the movement of the head in the socket, and therefore the extent of oscillation of the pin.

The last-pin carries, upon a shoulder 30 of the head 22, a last-bed-plate 32, which 95 supports the crown-portion of the cone of the last, holding it against movement longitudinally of the jack for the operations upon the lasted shoe. This bed-plate preferably includes two sections, the lower 34 being fast upon the head 22, and the upper 36 surrounding the pin which passes through an opening 38 in it, this upper section being free for limited movement along the pin. 100 It is held against separation from the fixed 105 plate and the extent of its movement deter-

mined by screws 40 passing through openings in the plate-section 34 and being threaded into the section 36. Heads 42 of these screws lie within counterbores of the 5 plate-openings, contacting with the inner extremities thereof at the limit of upward movement. The edges of the sections 34 and 36 adjacent to each other are inclined at 44, diverging outwardly to give a generally V-shaped depression. In this depression is located a continuous, expandible member, furnished by a helical spring 46, which is always under some tension, this 10 drawing the spring toward the bottom of the groove and holding the bed-plate-sections normally separated from each other. The diameter of the convolutions of the 15 spring is such that in this normal position, its outer side preferably projects somewhat beyond the peripheries of the plates, so that when a shoe is jacked, with the bed-plate-sections, as well as the last-pin, within it these 20 curved surfaces tend to deflect the upper, with its lining, outwardly, and prevent their 25 entrance between the bed-plate and the crown of the last.

In the operation of the machine, when pressure is applied to the lasted shoe, the 30 movable bed-plate-section 36 is depressed, expanding the spring 46 and causing this to emerge from its depression, as best appears in Fig. 2 of the drawing. This engages the lining of the upper about the entire support, thrusting it away, not only from the junction of the last and bed-plate, but also from the opposing surfaces of said bed-plate and the slide, placing it beyond danger of being 35 caught thereby and mutilated. When the pressure is removed, the spring 46 contracts to separate the bed-plate-sections, and is thus drawn into its depression, the parts 40 resuming their normal relation. Whatever position of self-adjustment the last-pin assumes in the operation of the machine, the bed-plate and lining-protector move with it, so that the relation of the lining-engaging 45 periphery of the spring 42 to the interior of the lasted shoe remains unaltered.

Having described my invention, what I 50 claim as new and desire to secure by Letters Patent of the United States is:

1. The combination with a last-support, of a continuous lining-protector surrounding the support and movable toward and from a lasted shoe.

2. The combination with a last-support, of an expandible member surrounding the support and arranged for contact with the interior of a lasted shoe.

3. The combination with a last-support,

of a work-engaging spring surrounding the support.

4. The combination with a last-support, of a helical shoe protector carried by the support and movable toward a lasted shoe. 65

5. The combination with a last-support, of a spring surrounding the support, and means for expanding the spring.

6. In a last-support, a last-supporting member including relatively movable sections, and a shoe-engaging spring movable by the sections and independently of said sections. 70

7. The combination with opposite last-supporting plates having a space between 75 their edges, of a lining-protecting member encircling the space.

8. The combination with opposite last-supporting plates having oppositely inclined edges relatively movable toward and from 80 each other, of a helical spring contacting with said edges.

9. In a jack, a last-pin, a last-bed-plate-section mounted in fixed relation to the pin, a bed-plate-section movable upon the fixed 85 section, and a lining protecting member encircling the plates and arranged to act upon the movable section.

10. In a jack, a last-pin, a last-bed-plate-section mounted in fixed relation to the pin, 90 a bed-plate-section movable upon the fixed section, a lining-protecting member encircling the plates and arranged to act upon the movable section, said plate-sections having converging inclined edges, and a helical 95 spring situated between said edges.

11. In a last-support, a last-pin arranged for universal movement, and a lining-protector carried by the pin and sharing in its 100 universal movement.

12. In a last-support, a last-slide, a last-pin movable thereon, and a lining-protector carried by the pin, all these elements being arranged to enter a lasted shoe.

13. The combination with a jack-top having a socket, a ball movable in the socket, a last-pin projecting from the ball, a last-bed-plate carried by the pin, and a member mounted for movement upon the bed-plate and arranged to engage a lasted shoe. 105

14. The combination with a jack-top having a socket, a ball movable in the socket, a last-pin projecting from the ball, a last-bed-plate carried by the pin and having relatively movable sections, and a work-engaging spring interposed between the sections. 115

In testimony whereof I have signed my name to this specification.

JOSEPH H. POPE.
